UNITED STATES PATENT OFFICE.

GEORGE F. SMITH, OF BALTIMORE, MARYLAND.

ROTARY OVEN.

1,401,824.

Specification of Letters Patent. Patented Dec. 27, 1921.

Application filed April 11, 1921. Serial No. 460,197.

To all whom it may concern:

Be it known that I, GEORGE F. SMITH, a citizen of the United States, residing at Baltimore, in the county of Baltimore City, and 5 State of Maryland, have invented certain new and useful Improvements in Rotary Ovens; and I do declare the following to be a full, clear and exact description of the invention, such as will enable others skilled in 10 the art to which it appertains to make and use the same.

This invention relates to an improved baker's oven and has special reference to a rotary turn-table positioned in the baker's oven 15 and provided with a vertically extending shaft which extends through the top of the oven and has its upper end secured in the upper section of a bearing which supports and rotatably mounts the shaft thus permitting 20 the shaft and turn-table to be rotated when the upper section of the bearing is rotated by actuating means.

Another object of the invention is to provide an improved type of turn-table having a 25 spider construction provided with improved arms and cross bars, the arms and cross bars being interlocked and having their upper faces flush so that the top of the turn-table which is formed of slabs of soapstone or other 30 suitable material may rest flat upon the spider.

Another object of the invention is to so construct this spider that the radiating arms and cross bars of the same may be easily put 35 together or taken apart and further so constructed that they will be firmly held in the proper position when set up.

Another object of the invention is to so construct the top of the table that the slabs 40 forming the same may be arranged in concentric circles and provide radiating rows of slabs which have their inner and outer and side edges meeting in contacting relation and their edge portions resting upon the radiating 45 arms and cross bars of the spider which supports the top.

This improved oven construction is illustrated in the accompanying drawings, where- 50 in:

Figure 1 is a view showing the oven in front elevation.

Fig. 2 is a vertical transverse sectional view through the oven taken along the line 2-2 of Fig. 3.

Fig. 3 is a vertical longitudinal sectional view taken along the line 3-3 of Fig. 1.

Fig. 4 is a vertical transverse sectional view taken along the line 4-4 of Fig. 3.

Fig. 5 is a horizontal sectional view taken along the line 5-5 of Fig. 3.

Fig. 6 is an enlarged fragmentary view of the turn-table showing the same in top plan.

Fig. 7 is a top plan view of one of the radiating arms of the spider forming a portion of the turn-table.

Fig. 8 is a side elevation of the arms disclosed in Fig. 7.

Fig. 9 is an enlarged transverse sectional view taken along the line 9-9 of Fig. 8.

Fig. 10 is a top plan view of one of the 70 cross bars which extend between the arms of the spider.

Fig. 11 is a view showing the cross bar of Fig. 10 in side elevation.

Fig. 12 is a transverse sectional view taken 75 along the line 12-12 of Fig. 10.

This turn-table has been shown in connection with an oven having a construction very similar to that disclosed in connection with the co-pending application, Serial No. 80 460,195, filed April 11, 1921. Since the specific construction of the body portion of the oven is described in detail in the application referred to, it will only be described briefly as follows.

This oven is provided with a combustion chamber 1 above the fire box and grate 2 and above the combustion chamber there is provided a baking chamber 3. The products of combustion pass from the combustion chamber through flues 4 into manifolds 5 and from these manifolds pass through pipes 6 into soot pockets 7 from which they pass through pipes 8 into manifolds 9. From the manifolds 9, the products of combustion pass into the flues 10 of a conduit 11 and then into the chimney 12. The flues 10 are formed in the conduit 11 by providing a dividing wall 13. The walls of the oven are thickened for the depth of the baking chamber 3 as shown in Fig. 5 thereby providing a baking chamber 90 which will be circular.

A turn-table is to be positioned in the baking chamber and in order to mount the same, there has been provided cross beams 14 105 which are preferably I-beams and carry a thrust bearing 15 to receive the lower end of a vertically disposed shaft 16. This shaft

16 extends through the wall 13 and top of the conduit 11 through the upper and lower members 17 and 18 of a bearing which is supported by cross beams 19. The upper bearing member 17 will be securely locked upon the upper end portion of the shaft 16 and is provided with a bevel gear 20 which meshes with a bevel gear or pinion 21 carried by an actuating shaft 22. This actuating shaft 22 is rotatably mounted in bearings 23 carried by the I-beams 19 and this shaft 22 extends through the forward wall of the oven and is provided with a hand wheel 24 by means of which the shaft 22 may be rotated when it is desired to rotate the shaft 16.

A spider is carried by this shaft 16 adjacent its lower end and within the baking chamber and is provided with a disk 25 which forms a hub and is locked upon the shaft 16 just above the bearing 15 so that when the shaft 16 rotates, this hub or disk will also rotate. The upper face of the disk is cut out thus providing upstanding concentric rings having openings 26 formed therein to receive fastener bolts 27 which also extend through sockets 28 formed in the inner end portions of the depending ribs 29 of the radiating arms 30. These arms 30 are T-shaped in cross section as shown in Fig. 9 and the depending ribs 29 thereof have their inner end portions cut away so that each arm will have its rib provided with an abutment shoulder 31 for engaging the outer periphery of the disk 25. Each arm is further provided with an upstanding abutment lip 32 at its outer end and intermediate its length will be provided with counter-sunk seats 33. From an inspection of Figs. 6 and 7, it will be seen that each of the seats 33 is formed with its end portions converging toward the outer end of the arm so that the end portions of the cross bars 34 may fit into the end portions of these seats with their ends meeting in end to end contact as shown clearly in Fig. 6. It will further be noted that the cross bars when in place will have their upper faces flush with the upper faces of the radiating arms thereby providing a spider having a smooth upper face. Each of these cross bars is provided with a depending rib 35 terminating short of the ends of the cross bar and adapted to engage the side edges of the radiating arms. The cross bars will therefore be prevented from moving longitudinally of the radiating arms and the cross bars will serve to prevent the radiating arms from having any tendency toward moving toward each other. The top of this turn-table is formed of slabs of soapstone or other suitable material. The two inner slabs 36 are semi-circular so that they may be set about the shaft 16 and rest upon the inner ends of the radiating arms above the hub disk 25. The remain-

ing slabs will each be in the form of a portion of a triangle and when put in place, will form concentric rings 37, 38 and 39 positioned about the central slabs 36. These slabs which form the rings 37, 38 and 39 will further be of such size that when put in place, they will just cover the spaces between the radiating arms and cross bars with their edge portions resting upon the arms and cross bars and meeting in edge-to-edge contact. The upstanding abutment lips 32 at the ends of the radiating arms engage the outer slabs and the slabs will thus be securely held in place and prevented from having any tendency to move apart.

It will thus be seen that there has been provided a turn-table which is so constructed that it may be mounted upon the shaft 16 and fit compactly in the lower portion of the baking chamber where it will take up a small amount of room and be positioned with its upper face approximately level with the lower edge of the door-way 40 through which articles are inserted and removed. If it is desired to take the turn-table apart for the purpose of making repairs or for cleaning the baking chamber beneath the turn-table, this can be easily done by simply removing the slabs and cross bars and then releasing the securing bolts 37 so that the radiating arms can be removed from the hub disk. The turn-table can be readily reassembled when desired.

I claim:

1. A turn-table for a baker's oven, said table comprising a rotatable shaft, a hub element carried thereby, radiating arms carried by the hub, said arms being provided in their upper faces with transversely extending V-shaped grooves forming countersunk seats, cross bars extending between the arms and having their ends fitting into the seats and meeting in end to end contact, and a top resting upon the arms and cross bars.

2. A turn-table for a baker's oven, said table comprising a rotatable shaft, a disk secured upon said shaft, radiating arms having depending webs and having their inner end portions overlapping the disk and cut to provide abutment shoulders engaging the disk, fasteners passing through the disk and inner ends of said arms, the arms being provided with transversely extending seats, cross bars extending between said arms and having their ends fitting into said seats in the upper faces of the arms, and a top resting upon the arms and cross bars.

3. A baker's oven having a baking chamber, a rotatable shaft extending vertically through the baking chamber, a spider carried by the shaft within the baking chamber and having a hub disk rigidly secured

upon the lower end portion of said shaft, arms secured to said disk and extending in diverging relation, each arm being T-shaped in cross section and having transversely extending seats in its upper portion, bars extending between said arms and having their end portions resting in said seats and

having depending ribs engaging the sides of said arms to hold the arms against transverse movement, and a top carried by the ¹⁰ spider.

In testimony whereof I have hereunto set my hand.

GEORGE F. SMITH.
